RUFUS SPAULDING MERRILL, OF HYDE PARK, ASSIGNOR TO HIMSELF, W. B. MERRILL, AND JOSHUA MERRILL, OF BOSTON, MASSACHUSETTS.

Letters Patent No. 104,624, dated June 21, 1870.

IMPROVEMENT IN LAMP-BURNERS.

The Schedule referred to in these Letters Patent and making part of the same.

To whom it may concern:

Be it known that I, RUFUS SPAULDING MERRILL, of Hyde Park, county of Norfolk and State of Massachusetts, have invented certain new and useful Improvements in Argand and other like Lamp-Burners; and I hereby declare the following to be a full, clear, and exact description of the same, reference being had to the accompanying drawing, in which—

Figure 1 is a sectional view of an Argand or round-wick burner, made in accordance with my invention.

Figure 2 is a perspective view of the chimney-holding springs, and perforated base or chimney-rest, detached from the other portions of the burner.

Figure 3 is a plan or top view of the removable portion of the burner shown in fig. 1.

My invention relates to Argand burners, or round-wick burners, in which a double current of air is employed to feed the flame, and is directed to cheapening and simplifying the construction of the burner, and to adapting it more perfectly for burning kerosene and other oils distilled from petroleum.

My invention relates,

First, to the formation of the removable portion of the burner, or that portion which is adapted to be slipped on or off the wick-tube.

Secondly, to the construction of the chimney-holding springs and the base; and

Thirdly, to means for supporting the chimney upon a seat raised above the base of the burner, for the purpose hereinafter stated; and to this end

My invention consists in the combination in an Argand burner, in which the chimney-holding device is removable, with external chimney-springs, of an annular perforated plate, and a sleeve fitting the wick-tube, or a tube encircling the wick-tube, the said plate extending transversely from the base of the springs, or from under the chimney-seat, to the said sleeve, when the external chimney-springs and the transverse annular perforated plate are formed of one piece of metal, substantially as hereinafter shown and set forth.

Also, in the combination of the foraminous base and chimney-springs, of a chimney-seatring, arranged within the space encompassed by the springs, and above the foraminous base, forming a rest for the chimney which will be raised above the perforated base, so as not to interfere with the free passage of the air up through the base into the burner.

The manner in which my invention is or may be carried into effect will be readily understood by reference to the accompanying drawing.

A is the wick-tube of an Argand burner, the construction of which is too well known to need further description.

Around the upper part of the tube, or around a tube encircling the same, is fitted the removable portion of the burner, consisting of the chimney-holding springs

a and perforated base *b*, which latter is united with a sleeve, *c*, which is the means of holding the parts in proper position relative to the wick and wick-tube, as shown in the drawing.

By employing a perforated base or diaphragm, *b*, to close the opening which, in ordinary Argand burners, intervenes between the wick-tube and the base of the chimney, when the latter is in position, I steady and regulate the draught, and divide into fine streams the air which enters the burner and passes up around the wick-tube to the flame, this being an important feature in Argand burners used for burning petroleum oils, as the flame is thereby prevented from flickering, the draught is made perfectly even, the air being finely divided and admitted in small streams only.

In order to manufacture the burner cheaply, and at the same time to render it very durable, and give it a finished appearance, I form the perforated base *b* and springs *a* from a single seamless sheet of metal, which is first struck up into a suitable cup or dish-form, and then has its sides cut or stamped out to form the springs *a*, and its bottom struck up and punched, or otherwise manipulated, so as to form the annular perforated base *b*, as clearly shown in fig. 2.

The springs and base are thus formed solidly, and without a seam, from the same piece of metal, and, being produced entirely by machinery, are better and much more quickly made, and present a more highly finished appearance, than were they made separately and afterwards soldered together.

The base of the chimney, if desired, can rest directly upon the perforated diaphragm *b*, but in some instances it may be found advisable to allow the whole of the perforated base to remain exposed for the passage of air, and to support the chimney upon a ring or ledge, *d*, such as shown in the drawing, which is raised above the base, and supported in place in any suitable manner by being soldered or otherwise fastened to the springs or sides of the burner, or by means of a flange which rests upon the base, the latter mode being represented in the drawing. This ring may also be inclined a little upward, as shown in fig. 1, so as to act in some sort as a deflector, directing the air which enters through the base toward the flame; and I can form upon the ring, projections or ridges *e*, upon which the chimney will rest, so as to leave, between the base of the chimney and the main portion of the ring, spaces through which the air can enter from the sides of the burner. There would thus be two currents of air in the burner, the one entering above the ring and the other below it, the latter being directed toward the wick by the inclination of the ring.

Having now described my invention, and the manner in which the same is or may be carried into effect,

What I claim, and desire to secure by Letters Patent, is—

In an Argand burner, in which the chimney-holding

device is removable, the combination with external chimney-springs, of an annular perforated plate and a sleeve fitting the wick-tube, or a tube encircling the wick-tube, the said plate extending transversely from the base of the springs, or from under the chimney-seat to the said sleeve, and when the external chimney springs and the transverse annular perforated plate are formed of one piece of metal, substantially as herein shown and set forth.

Also, the combination, with the foraminous base and chimney-springs, of a chimney-seat ring or ledge, arranged within the space inclosed by the springs, and

above the foraminous base, as and for the purposes shown and set forth.

Also, the employment, in combination with the chimney-springs and foraminous base, of a raised chimney-seat ring, constructed with ridges or projections, substantially as described, for the purposes stated.

In testimony whereof, I have signed my name to this specification before two subscribing witnesses.

RUFUS S. MERRILL.
